UNITED STATES PATENT OFFICE.

SALVADOR CARRAU AND WARREN RICHARDSON COBEAN, OF BUENOS AIRES,
ARGENTINA.

DEVICE FOR THE USE OF CARBON PAPER IN TYPEWRITERS.

Application filed March 16, 1921. Serial No. 452,864.

To all whom it may concern:

Be it known that SALVADOR CARRAU, and WARREN RICHARDSON COBEAN, citizens of Argentina and United States, respectively, 5 and residents of Buenos Aires, Argentina, have invented certain new and useful Devices for the Use of Carbon Paper in Type-writers, of which the following is a specification.

10 This invention relates to a device which, when applied to typewriters allows the utilization and use of carbon sheets with ease and rapidity and a great economy of work and time.

15 The insertion of carbon sheets, is, as is well known a slow and troublesome operation, which at times is somewhat difficult if sufficient space is not available on the writing desk; air currents being specially troublesome, as they blow the carbon sheets away. The time wasted by a typist during the day in uniting the sets of writing paper fifty, eighty and often a hundred times, is quite evident, after which the typist has again to 25 waste valuable time in taking the sheets apart every time a letter is finished.

If the said carbon sheets are placed together in one set into the typewriter, extracting only the written sheets of paper 30 once the page has been finished, and afterwards inserting the blank writing paper sheets, the economizing of time and labor is considerable, as only a small space is required on the writing desk and there is no 35 need of extending the papers on same. As above stated the blank sheets are easily and rapidly inserted by the use of this invention, as the carbon papers are fixed in one set in the typewriter and do not need removing 40 every time a new sheet is to be typed.

A form of device embodying this invention is hereinafter described with reference to the accompanying drawings in which:

Fig. 1 is a plan view of the device before 45 the carbon sheets have been placed on same;

Fig. 2 is a similar view illustrating the sheets of paper placed in position;

Fig. 3 is a longitudinal section of Fig. 50 1; and

Fig. 4 is a sectional view of the device placed between the printing roller and the paper holder rollers of a typewriter.

As illustrated in the said figures, the device consists of a backing sheet *a*, longer 55 than the sheets of carbon paper, and on

which the lower portions of the latter can be stuck or attached to gummed strips *b*, *b'* etc., forming what may be termed counter-foils as best illustrated in Fig. 3. The sheets of carbon paper *e* may be also sewed 60 with string, wire or any other suitable material. The counterfoils comprise several strips of gummed paper on which are attached as many sheets of carbon paper as are required. The outer strip *b* of the "booklet" serves to facilitate the backward movement in the typewriter of the set of papers placed in the device, as for this purpose the roller of the typewriter must be moved backwards or in a counter-clockwise 70 direction. The space indicated by letter *d* in the figures, represents a prolongation which is one of the characteristics of this invention. This prolongation is the part which is held fast in the typewriter 75 and projects below the platen or printing roller when the last line of the sheet of paper is reached, thus allowing the written pages to be withdrawn without any need of removing also the carbon sheets. 80 The latter therefore always remain in place and ready to receive the new sheets of blank paper, which are inserted between the carbon sheets after which the device together with the said sheets is returned to the starting point by pulling on the prolongation *d*. At the other end this device can be provided with a protruding portion *c* which being doubled over the edges of the sheets of paper 85 serves as a guide for the first insertion of 90 same into the typewriter.

Operation.—The utilization of the device does not require further explanation. On placing it in the typewriter with the folded portion *c* in advance, the roller *g* is rotated 95 in a clockwise direction until the lower part or prolongation *d* of the device only is gripped. Then the blank sheets *f* are placed between the carbon papers and the roller *g* is rotated in an opposite direction until the 100 blank sheets are brought to a position to allow the starting of the typing on the inserted sheets of paper. When the typing is finished, the roller *g* is rotated in a clockwise direction until the device is held in the typewriter by the prolongation *d* only; and then the written sheets of paper can be withdrawn. This operation eliminates in a great 105 measure the loss of time usually caused by withdrawing the written sheets of paper one 110

by one from between the carbon papers everytime a sheet has been typed and then new sheets inserted between the carbons when a new set of sheets have to be typed.
5 In the present device the sheets of carbon paper are always held together and conveniently mounted in order to eliminate the troublesome operation as used at present, as it is only necessary to insert the blank sheets
10 of paper every time they have to be typed.

It is understood that the construction and mode of operation above described may be varied as to details according to the preference of the operator, as for example, a textile
15 may be used instead of paper, and the manner of inserting the device with the carbon and writing paper may be the reverse of that described. The manner of fastening the carbons to the "counterfoils" as described is
20 not material to the invention, since the use of gummed strips may be substituted by any other way of fastening the multiple carbons to the backing sheet.

Having thus described the invention,
25 what we claim and desire to protect by Letters Patent of the United States of America, is:

1. A device for facilitating the making of carbon copies with a typewriter comprising
30 a backing sheet provided with a folded end portion, a series of superposed tabs, each having one of its ends attached to the end portion of the backing sheet which is opposite to the folded end portion of said backing

sheet, an extension projecting from the end 35 of the backing sheet to which the tabs are attached, and carbon sheets superposed on said backing sheet, each of said carbon sheets having one of its ends connected to the free end of one of the tabs.
40

2. A device as claimed in claim 1 in which the tabs are provided with an adhesive substance to which the carbon sheets are secured.

3. A device for facilitating the making 45 of carbon copies with a typewriter comprising a backing sheet provided with a folded end portion, carbon sheets superposed on the said sheet and fastened thereto, said folded end portion positioned to envelope the free 50 ends of said carbon sheets and letter sheets therebetween, and an extension projecting from the end portion of the backing sheet which is opposite to the folded end portion of said backing sheet adapted to be retained 55 by the rollers of the typewriter machine after the entire page has been typed, to facilitate the placing of new writing sheets within the device without removing the device from the writing machine.
60

Signed at Buenos Aires, Argentine Republic this thirty-first day of January A. D. 1921.

SALVADOR CARRAU.
WARREN RICHARDSON COBEAN.
